ALEXIS R. PRIBIL, OF DETROIT, MICHIGAN, ASSIGNOR, BY MESNE ASSIGNMENTS, TO
GEORGE W. BOWEN, OF AUBURN, NEW YORK.

GREASE-CUP.

1,107,350.

Specification of Letters Patent. Patented Aug. 18, 1914.

Application filed September 10, 1912. Serial No. 719,521.

To all whom it may concern:

Be it known that I, ALEXIS R. PRIBIL, a citizen of the United States of America, residing at Detroit, in the county of Wayne 5 and State of Michigan, have invented certain new and useful Improvements in Grease-Cups, of which the following is a specification, reference being had therein to, the accompanying drawings.

10 In the use of compression grease cups it is desirable that they be so constructed that their movable parts are securely locked when the cups are filled and mounted in position. Also when grease cups are manufactured or applied in large quantities, it is 15 desirable that they be so designed as to contain a minimum amount of material and possess a maximum capacity.

This invention relates to compression 20 grease cups and to a construction thereof whereby the movable parts are securely held in position, and whereby the cost of production both for labor and material is reduced and the greatest capacity for the material 25 used is obtained.

The invention consists in the matters hereinafter set forth and pointed out in the appended claims.

In the drawings, Figure 1 is a view, partially in longitudinal section and partially in elevation, of a compression grease cup embodying features of the invention; Fig. 2 is a top plan view of the cup; Fig. 3 is a view in detail and in section on line III—III of Fig. 1; and Fig. 4 is a view in section looking upwardly taken on or about line IV—IV of Fig. 1, the rim flange or annular part of the base being omitted.

As herein shown a base 1 of suitable material has a longitudinally apertured nipple 2 that is exteriorly screwthreaded or otherwise provided with means for attaching to a bearing or machine to be lubricated. An interiorly screwthreaded rim 45 flange or annular part 3 is formed on or secured to the base, and preferably projects from the top thereof. A locking member 4 is supported on the base, being preferably arranged within the flange or annular part 50 3. As illustrated, this locking member is a flat spring having its central portion mounted on a seat, as a boss 5, provided on the top or upper end surface of the base 1 within, and substantially concentric with, and 55 spaced apart from, the flange or annular

part 3, the spring being preferably fixed in position on its seat by a turned-over retaining flange 6 on the central portion of the upper face of the seat or boss 5. This spring or locking member 4 is provided with 60 arms extending toward the flange or annular part 3 and spaced apart from the opposing surface of the top of the base interposed between the seat 5 and the annular part 3, which surface is shown as depressed 65 below the seat 5; and said arms of the locking member are provided with radial ribs or projections 7 struck up or formed on their outer portions which lie adjacent to the rim flange 3. Although the locking member or 70 spring 4 is here illustrated as provided with a plurality of yielding portions or arms, it is obvious that one or more of these arms may be dispensed with.

An inverted cup-shaped grease retaining 75 cap 8 with upper portion 9 that may be knurled, or otherwise fitted for convenient manipulation, is screw-threaded at its open lower end into the flange 3, and the marginal lower edge of said open end bears 80 downwardly against, and coacts with, the locking member 4. Preferably, marginal notches, indicated at 10, are provided in the lower edge of the cap and are adapted to yieldingly interlock with the projections 7 85 of the locking member 4. A compression piston or disk 11 with suitable packing washer 12 fits within the cap in screw-threaded engagement with the lower end of a spindle 13. This piston is non-revoluble 90 within the cap 8 and is movable axially in said cap as the spindle 13 is revolved. Said spindle projects within the cap 8 and above its closed end 14 and is rotatable in a guide opening in the closed end 14 by means of a 95 suitable handle 15 on the upper end of the spindle above the closed end of the cap 8, said spindle and handle constituting the operating member for the piston 11. Preferably, the handle is screw-threaded onto the 100 spindle and locked in position by a pin 16 or the like, and abut a ferrule 17 of spring material that encircles the spindle and has a flared base flange 18 which rides on a roughened, knurled or notched face indicated at 19 on the outer face of the cap head 14. Sufficient pressure is put on the ferrule 17 by screwing the handle 15 on the spindle when assembling the cup to cause the ferrule to yieldingly coact with a shoulder 20 110

on the spindle to hold the latter against longitudinal movement. The frictional engagement or interlocking of the roughened rim flange 18 of the ferrule and the face 19 of the cap holds the spindle from accidental rotation and thereby prevents movement of the compression disk 11. As a result of this construction a grease cup is obtained which may be made of very light material, is of large capacity and has its movable parts locked when the cup is filled and assembled in the position desired by the operator so that said parts are not displaced by the jarring of the support for the grease cup. Furthermore, the plunger cannot work down to eject grease when it is not desired. Because of the simplicity of construction and lightness the cost of the cup is low while it is efficient and its parts are not readily lost.

Obviously, changes in the details of construction may be made without departing from the spirit of my invention and I do not limit myself to any particular form or arrangement of parts.

What I claim is:—

1. In a grease cup, the combination of a base having an annular part, an inverted cup-shaped cap having its open end turning within the annular part, and a locking member arranged within the annular part and fixed to the base and having a portion thereof spaced apart from, and yielding relatively to, the opposing surface of the base, and detachably engaging the wall of the open end of the cap for holding the cap from turning relatively to said annular part, substantially as and for the purpose set forth.
2. In a grease cup, the combination of a base having an annular internally threaded part; an inverted cup-shaped cap having its open end externally threaded and screwing within the annular part, and a locking member arranged within the annular part and fixed to the base and having a portion thereof spaced apart from, and yielding relatively to, the opposing surface of the base, and detachably engaging the wall of the open end of the cap for holding the cap from turning relatively to said annular part, substantially as and for the purpose specified.
3. In a grease cup, the combination of a base having an annular part and a seat arranged within the annular part and spaced apart therefrom, an inverted cup-shaped cap having its open end turning within the annular part, and a locking member mounted on the seat and having a portion thereof projecting beyond the seat toward the annular part and spaced apart from, and yielding relatively to, the opposing surface of the base, the extremity of said yielding portion detachably engaging the wall

of the open end of the cap for holding the cap from turning relatively to said annular part, substantially as and for the purpose set forth.

4. In a grease cup, the combination of a base having an annular internally threaded part and a seat arranged within the annular part substantially concentric therewith and spaced apart therefrom, an inverted cup-shaped cap having its open end externally threaded and screwing within the annular part, and a locking member mounted on the seat and having an arm projecting beyond the seat toward the annular part and spaced apart from, and yielding relatively to, the opposing surface of the base, the extremity of the arm being provided with means detachably engaging the wall of the open end of the cap for holding the cap from turning relatively to said annular part, substantially as and for the purpose described.

5. In a grease cup, the combination of a base having an annular part and a seat arranged within the annular part and spaced apart therefrom, an inverted cup-shaped cap having its open end turning within the annular part, and a locking member having its central portion mounted on the seat and having arms projecting in different directions beyond the seat toward the annular part and spaced apart from, and yielding relatively to, the opposing surface of the base, the extremities of the arms being provided with means detachably engaging the wall of the open end of the cap for holding the cap from turning relatively to said annular part, substantially as and for the purpose specified.

6. In a grease cup, the combination of a base having an annular part, a seat arranged within the annular part, and a surface interposed between the annular part and the seat and depressed beneath said seat, an inverted cup-shaped cap having its open end turning within the annular part, and a locking member mounted on the seat and having a portion thereof projecting beyond the seat above said depressed surface and toward the annular part, said portion of the locking member being spaced apart from, and yielding relatively to, said depressed surface and detachably engaging the wall of the open end of the cap for holding the cap from turning relatively to said annular part, substantially as and for the purpose set forth.

7. In a grease cup, the combination of a base having an attaching nipple and a rim flange, a boss on the upper face of the base, a spring plate secured to the boss with arms extending toward the flange above the base and a cap detachably engaging the flange and interlocking with the arms when forced home.

8. In a grease cup, the combination of a base, a rim flange on the base and a central boss on the upper face of the base, with a spring plate rigidly secured near its center 5 on the boss, spring arms extending from the plate, projections on the arm extremities, and a cap detachably engaging the rim flange and having a notched margin that engages with the projections when the cap 10 is forced home.
9. In a grease cup, the combination of a base having an annular part, an inverted cup-shaped cap having its open end turning within the annular part, a locking member 15 arranged within the annular part and fixed to the base and having a portion thereof spaced apart from, and yielding relatively to, the opposing surface of the base, and detachably engaging the wall of the open 20 end of the cap for holding the cap from turning relatively to said annular part, and means within the cap for ejecting the grease, substantially as and for the purpose set forth.
10. In a grease cup, the combination of a base having an annular internally threaded part and a seat arranged within the annular part, an inverted cup-shaped cap having its open end externally threaded and screwing 25 within the annular part, a locking member having its central portion mounted on the seat and having arms projecting in different directions beyond the seat toward the annular part and spaced apart from, 30 and yielding relatively to, the opposing surfaces of the base, the arms detachably engaging the wall of the open end of the cap for holding the cap from turning relatively to said annular part, and means carried by 35 the closed end of the cap and movable within the cap relatively thereto for ejecting the grease, substantially as and for the purpose specified.
11. In a grease cup, a base, an attaching 40 nipple depending from the base, a rim flange on the base, a boss on the upper face of the base within the flange, a spring plate rigidly supported on the boss with arms extending toward the rim flange above the 45 base, a cap in screwthreaded engagement with the rim flange provided with notches on its lower margin with which the spring arms engage when the cap is forced home, and means for ejecting the contents of the 50 cap through the base.
12. In a grease cup, the combination of a base, an inverted cup-shaped cap detachably mounted on the base, a piston within the cap and non-revoluble relatively thereto, an 55 operating member journaled in the closed end of the cap, one end of the operating member being within the cap and coacting with the piston for moving the same axially in the cap, and the other end of the operating member projecting above the closed end of the cap, one end of the operating member being within the cap and coacting with the piston for moving the same axially in the cap, and the other end of the operating member projecting above the closed end of the cap, said operating member being provided with a shoulder, and yielding means mounted on the operating member and coacting with the shoulder and the opposing surface of the cap for holding the operating member from revolving relatively to the cap, substantially as and for the purpose set forth.
13. In a grease cup, the combination of a base, an inverted cup-shaped cap detachably mounted on the base, a piston within the cap and non-revoluble relatively thereto, an 70 operating member journaled in the closed end of the cap, one end of the operating member being within the cap and coacting with the piston for moving the same axially in the cap, and the other end of the operating member projecting above the closed end of the cap, said operating member being provided with a shoulder, and yielding means mounted on the operating member and coacting with the shoulder and the opposing surface of the cap for holding the operating member from revolving relatively to the cap, substantially as and for the purpose set forth.
14. In a grease cup, the combination of a base, an inverted cup-shaped cap detachably mounted on the base and having an outer surface of its closed end roughened, a piston within the cap and non-revoluble relatively thereto, an operating member journaled in the closed end of the cap, one end of the operating member being within the cap and coacting with the piston for moving the same axially in the cap, and the other end of the operating member projecting above the closed end of the cap, the operating member being provided with a shoulder above the closed end of the cap, and yielding means mounted on the operating member and coacting with said roughened surface on the cap and the shoulder on the operating member for holding the operating member from revolving relatively to the cap, substantially as and for the purpose described.
15. In a grease cup, the combination of a base having an annular part, an inverted cup-shaped cap having its open end turning within the annular part, means for holding the cap from turning relatively to said annular part, a piston non-revoluble within the cap, an operating member revoluble in the closed end of the cap and having one end coacting with the piston for moving the same axially in the cap, and yielding means 90 on the outside of the cap coacting with the cap and said other end of the operating member for holding the operating member from revolving relatively to the cap, substantially as and for the purpose set forth.
16. In a grease cup, a base, an attaching nipple depending from the base, a rim flange on the base, a cap in screwthreaded engagement with the rim flange, means for holding the cap from turning relatively to the cap.

the rim flange, a spindle rotatable in the top of the cap, a handle on the upper part of the spindle, a spring ferrule in compression between the handle and the cap, and a compression plunger in the cap in screwthreaded engagement with the spindle.

17. In a grease cup, a base, a longitudinally apertured attaching nipple depending from the base, a flange on the rim of the 10 base, a cap in screwthreaded engagement with the rim flange, means for holding the cap from turning relatively to the rim flange, a roughened annular face on the upper end of the cap, a spindle rotatable 15 through the head of the cap concentric with

the roughened face, a plunger in the cap in screwthreaded engagement with the spindle, a handle on the outer end portion of the spindle, and a ferrule encircling the spindle between the handle and the head of 20 the cap and having a flared spring rim adapted to yieldingly engage the annular face on the cap head.

In testimony whereof I affix my signature in presence of two witnesses.

ALEXIS R. PRIBIL.
